SUCTION CLEANER

Harry B. White, Canton, Ohio, assignor to The Hoover Company, North Canton, Ohio, a corporation of Ohio

Application December 21, 1940, Serial No. 371,126

10 Claims. (Cl. 15—16)

This invention relates to improvements in suction cleaners and more particularly to improved means for working the dirt and litter from the filter bag of a suction cleaner and packing it into a separate removable receptacle, thereby making it possible for the cleaner to be operated for longer periods of time without disposing of the accumulation of dirt.

Perhaps the simplest application of a dirt compactor to a suction cleaner is that of a reciprocating dirt feeding member mounted in the discharge opening at the lower end of a filter bag and toward which the dirt and litter gravitate, thence to be forced into a removable collecting receptacle. Such an arrangement has been disclosed in an application filed November 18, 1939, and bearing Serial No. 305,058, wherein the compacting member is actuated by power derived from the swinging movement of the cleaner handle and transmitted through a suitable drive mechanism.

While the swinging of the handle affords an adequate source of power for actuating the compacting mechanism, it has one disadvantage, namely, that the arc through which the handle swings is commensurate with the length of the forward and return strokes of the cleaner over the carpet surface and since these strokes are comparatively short, the compacting strokes will be made up of an intermittent succession of short steps incapable individually of producing an effective feeding action of the compacting mechanism.

Therefore, the object of the present invention is to provide an improved drive mechanism whereby effective feeding strokes will be imparted to the compacting member, irrespective of the exact nature of the handle movement. In a word, the drive mechanism acts to advance the compacting member step by step with each up and down movement of the handle throughout one stroke (preferably the feeding stroke) and completes the other stroke with a "quick-return motion," so that the time interval between the feeding strokes of the compacting member is practically eliminated.

And a further object of the invention is to provide a novel compacting mechanism consisting of a claw-like compacting member which follows one path throughout its feeding stroke but returns in a different path, thus partaking of much the same movement that a person might use in emptying a bag or receptacle by removing its contents, a handful at a time.

A preferred embodiment of the improved com-

pactor drive mechanism has been illustrated in the accompanying drawings, in which:

Figure 1 is a general view of a suction cleaner showing the essential parts of the compactor drive mechanism in side elevation;

Figure 2 is an enlarged detail view in side elevation of the compactor drive mechanism;

Figure 3 is a view in cross section through the compactor assembly as taken on line 3—3 of Figure 2;

Figures 4 and 5 are detail views in perspective showing the track and sliding block arrangement that controls the tilting of the compactor slide bar; and

Figure 6 is a view in side elevation of the compacting mechanism in tilted position.

The suction cleaner to which a dirt compactor is especially applicable is one of the portable handle-maneuvered types, consisting generally of a body or casing 1, mounted upon wheels and provided with a handle 2 having pivotal mounting adjacent the rear end of the casing and free to swing in a vertical plane during the movement of the cleaner over the carpet surface. The extreme arc through which the handle swings is about 90 degrees, that is, between a vertical or storage position and a rearward and horizontal position, although in normal operation, the swinging movement of the handle is probably not over 30 degrees or 15 degrees above and below a mean handle angle of say 45 degrees, depending upon the way in which the cleaner is manipulated.

The type of cleaner herein illustrated follows the more orthodox design in that the suction-creating motor and fan unit is carried by the casing 1 which in turn is supported upon pairs of front and rear wheels 3 and 4, respectively. A nozzle 5 with its downwardly facing nozzle mouth spaced in close proximity to the carpet surface forms the forward portion of the casing 1. At the rear end of the casing 1 is a flanged outlet connection 6 leading from the fan chamber of the suction-creating unit and ultimately having connection with a filter bag 7 mounted below and supported at its upper end by the handle 2.

But intermediate the outlet connection 6 and the dirt bag 7 is a hinged adapter 8 including a flexible bellows section 8a connecting two hinged-together fittings 8b and 8c, the outermost fitting 8c having a tubular extension or conduit 9, terminating in an annular collar or frame 10 of enlarged diameter for the lower end of the dirt bag 7. This bag is of the usual construction used

for filtering purposes, being either of a special porous cloth or paper as desired. The upper end of the bag is normally closed and detachably suspended from the handle, whereas its lower open end, only slightly restricted, fits over and is clamped to the outer end of the annular frame 10, as shown in Figure 1. This supporting frame for the lower end of the filter bag is practically twice the diameter of the conduit 9 and has an internal conical wall segment 10a supporting at its center a gland or stuffing-box 11 for a reciprocating slide-rod 12 which projects into the lower end of the bag 7 and carries at its end an L-shaped finger or claw 13.

Now, offset below the discharge end of the conduit 9 there is formed a rectangular opening 14 in the annular frame 10 in line with the path of the slightly curved blade 13a of the compacting member 13, as shown in Figure 3. And communicating with the lower end of the filter bag 7 through the opening 14 is a disposable dirt collecting receptacle 15 preferably having the form of a heavy paper bag adapted to have its open end fitted over and suitably clamped to a flange 14a surrounding the discharge opening 14 on its underside.

The action of the compacting member 13 may be characterized generally as a reciprocating movement toward and from the opening 14 which communicates directly with the space at the lower end of the filter bag, the member 13 pushing a quantity of the dirt and litter ahead of it into the receiving receptacle during each feeding stroke and then reaching into the bag for another batch with a sort of raking or clawing motion.

The endwise sliding rod 12, carrying the fixed claw-like member 13 at its operating end, is supported in a tiltable frame 16 extending along one side of the conduit 9 and receptacle 15 just behind the annular supporting frame 10 and pivotally mounted at its forward end to rock about a transverse horizontal axis at the beginning and end of each return stroke. The frame 16 also carries the mechanism which imparts the reciprocating movement to the compactor slide-rod 12, this mechanism consisting primarily of a sprocket chain 17 carried on sprocket pinions 18, 18, journaled at opposite ends of the frame 16, which is elongated in the direction of movement of the slide rod, as clearly shown in Figure 2. The sprocket pinion 18 at the forward end of the frame 16 is journaled on a pivot pin 19 anchored in a vertically arranged boss 20 integral with the rear face of the annular bag supporting frame 10, said pin also forming the pivotal support for the frame 16 and about which it rocks intermittently through a small angle. In its normal position the frame 16 extends parallel with the conduit 9, as shown in Figure 2, and from that position tilts downwardly to the inclined position, shown in Figure 6. Opposing the tilting of the frame 16 is a compression spring 21 extending between the underside of the frame 16 at a point just rearwardly of its axis of tilting and a fixed bracket 22 mounted below the frame and onto the rear wall of the annular bag supporting frame 10.

Carried by and extending lengthwise of the frame 16 just outwardly from the vertical plane of the sprocket chain 17 is a guide bar 23 on which is slidably mounted a cross head 24 having the form of a vertically arranged hollow block to the front face of which is attached the rear end of the slide-rod 12, as clearly shown in Fig-

ures 4 and 5. The cross head 24 faces along its inner vertical edge, a spreader rail 25 projecting laterally from the opposite side wall of the frame 16 into the space between the top and bottom leads of the sprocket chain 17, said rail 25 serving to prevent the leads of the sprocket chain from being forced toward each other when pressure is applied to one or the other in a vertical direction and as occurs during the operation 10 of the frame tilting devices presently to be described.

The cross head 24 is open along its side edge facing the sprocket chain 17 and extending endwise into this open edge is a roller 26 journaled 15 upon an extension of one of the pins connecting adjacent links of the sprocket chain, as clearly shown in Figure 5. The height of the cross head is equal to the vertical distance separating the top and bottom leads of the sprocket chain so 20 that as said chain is driven say, in a clockwise direction, the cross head 24 travels back and forth with a uniform reciprocating movement while the roller 26 rides up and down within the cross head as it passes around the sprocket pinions 18.

Now, the sprocket chain 17 is driven through the forward sprocket pinion 18 by means of a pawl and ratchet mechanism consisting of a ratchet wheel 27 fixed to and rotative with the driving sprocket pinion 18 and engaged by a pawl 28 pivotally mounted upon the face of an oscillating plate 29 journaled upon the same pivot pin 19 that supports the driving sprocket pinion 18 and ratchet wheel 27. Connected with the oscillating plate 29 at a point offset from the pawl 28 is a link 30 extending substantially parallel with the handle 2 to a point just short of the outlet connection 6 from the cleaner casing where it connected to a crank arm 31 carried by a shaft 32 journaled on a suitable bearing bracket 30 with its axis coinciding with the horizontal transverse axis of the hinge connecting the adapter fitting. A spur gear 34 is also mounted on the shaft 32 and this gear wheel meshes with a gear sector 35 forming an integral part of the lower end of the handle 2 with its center coinciding 45 with the handle axis as marked by its pivot pin 2a.

Thus it is apparent that as the handle 2 is moved up and down during the forward and backward strokes of the cleaner over the carpet surface, this movement is transmitted to the crank arm 31, through the spur gear 34, gear sector 35 and link 30 to the oscillating plate 29 forming the carrier for the driving pawl 28, the latter being spring-pressed in contact with the ratchet wheel 27 and assisted by a companion pawl 28a engaging said ratchet wheel at a point diametrically opposite. Thus, every oscillation of the crank arm 31 is transmitted to the pawl 28 which in turn advances the ratchet disc and its associated sprocket pinion 18 in a clockwise direction and through an arc proportional to each oscillation of the handle-driven crank arm 31.

As thus far described, the compactor drive mechanism would function to impart an intermittent reciprocating movement to the slide rod 12, with the compacting member 13 moving toward and from the opening 14 and the collecting receptacle 15 in successive short steps with each up or down movement of the handle. However, as previously explained, it is desirable that the slide rod carrying frame 16 be tilted downwardly at the completion of each feeding stroke so that the compacting member 13 will follow 70 a different path through the accumulation of dirt

and litter during its return stroke. The means for accomplishing this tilting movement will now be described:

Attached to and carried by the sprocket chain 17 is a cam member in the form of a U-shaped shoe 36 pivotally connected at one end to the sprocket chain 17 immediately behind the roller 26 as regards its direction of movement, the free portion of the shoe trailing to the rear of its point of attachment. Now, when the shoe is moving with the bottom lead of the chain, it slides in contact with the bottom wall 16a of the tilting frame 16 and, with the sprocket chain being driven in a clockwise direction, it will be evident that the shoe 36 will follow the roller 26 around the sprocket pinion 18 at the rear or free end of the frame 16 from the bottom to the top lead of the chain.

It may be explained at this point, that during the movement of the cross head 24 from right to left, that is to say, during the feeding stroke of the slide rod 12, it is necessary to retain the frame 16 positively against downward tilting movement and to accomplish this, an angle plate 37 is secured to the outer face of the conduit 9 just above the frame 16, with the flange 37a along its lower edge extending parallel with and just above the upper lead of the sprocket chain 17. Also, carried by the cross head 24 is a finger 24a offset above the top surface thereof just enough to ride in contact with the top face of the track flange 37a during the feeding stroke of the compacting member, as clearly shown in Figures 4 and 5. Thus, as long as the finger 24a of the cross head 24 rides on top of the track flange 37a, the frame 16 is held against downward tilting movement. But it will be noted that at a short distance inwardly from the rear or far end of the track flange 37a, there is a marginal slit 37b formed in its edge by two kerfs at right angles to each other and the partially severed portion 37c bent upwardly so that the slit faces endwise and toward the rear end of the track flange.

Now, returning to the action of the shoe 36 in effecting the tilting of the frame 16, it should be noted first that during the movement of the cross head 24 from right to left, that is, during the feeding stroke of the compacting member 13, its guide finger 24a slides along the top side of the track flange 37a and on approaching the end of the stroke passes over and beyond the endwise opening slit 37b. However, as it begins its forward or return stroke, the finger 24a slides through the slit 37b and thence beneath the track flange 37a, whereupon the frame 16 is now free to be tilted downwardly providing a tilting force is applied thereto and this is the function of the shoe 36 which, upon being carried around the rear sprocket pinion 18 is brought into contact with the underside of the track flange 37a just after the finger 24a on the cross head 24 has passed from the top to the underside of the track flange. Thus, the shoe 36 coming into contact with the underside of the track flange 37a rocks the rear end of the frame downwardly to the position shown in Figure 6 and sliding forwardly along the underside holds the frame in tilted position until it encounters an upwardly sloping guideway 37d at the forward end of the track, whereupon the shoe leaves the track flange and permits the frame 16 to rock back into its normal position under the tension of the spring 21. And finally, as the cross head again begins its succeeding feeding stroke with the frame now parallel with the track 37a, the finger 24a on the 75

cross head passes above the track flange 37a once again and locks the frame 16 against tilting during the remainder of the feeding stroke. In this manner, the compacting element 13 follows a line directly toward the discharge opening 14 into the collecting receptacle during its feeding stroke but returns along a line angularly disposed to the line of the feeding stroke.

It might also be pointed out in connection with the tilting movement of the frame 16 and the slide rod 12, that it is necessary for the gland or stuffing box 11 to shift with the slide rod and for this reason it is preferred to mount the stuffing box at the center of a corrugated or otherwise flexible disc 38 forming the bottom of the conical wall section 10a.

The remaining feature to be disclosed is the mechanism for imparting the so-called "quick-return" motion to the slide rod during its return stroke.

This quick return mechanism consists primarily of a drum 40 carried on the underside of the frame 16 near its tiltable free end, said drum being relatively supported upon a bracket 41 although its rotation is opposed by a helical spring 42 mounted within the drum with one end fixed to the spindle 41a supporting the drum and the other end of the spring fixed to the periphery of the drum. The spring is so arranged that the drum can be rotated in a counter-clockwise direction at the same time winding up the spring. Now, wrapped around the periphery of the drum is a strap 43, the turns being wound in a clockwise direction with a straight lead from the top 30 of the drum extending along the bottom wall 16a of the frame 16, around the outside of a pulley 44 journaled at the extreme pivot end of the frame 16 thence upwardly at right angles to a second guide pulley (not shown but in line with the center line of the sprocket chain 17), and thence to the front face of the cross head 24, as clearly shown in Figure 4.

With this spring-drum arrangement, it is apparent that during the feeding stroke, that is, with the cross head moving from right to left, the strap 43 is being unwound from the drum 40 while the spring 42 is being wound up. Thus, when the cross head reaches the end of its feeding stroke, the tension on the spring 42 in the drum has been built up to such a point that immediately the roller 26 passes upwardly and over the outer sprocket pinion 18, the spring tension pulls the cross head forward with a rapid movement, thus completing the return stroke and almost immediately whereupon the feeding stroke then follows at the usual rate of speed. It is clear that the action of the locking pawl 28a prevents this return movement until it can be accomplished by the movement of the cross head moving roller 26 along the top of the chain. In this way, the dirt in the filter bag has an opportunity to work its way toward the opening 14 at the bottom of the bag whereupon the compacting member 13 slowly forces a portion into the collecting receptacle and then is quickly shifted back to start another feeding stroke, although in the interval the entire compactor assembly is tilted so that the claw-like compacting member 13 is permitted to ride over the accumulation of dirt during the return stroke and into position behind the mass of dirt as the feeding stroke begins.

Thus two advantageous features are incorporated in the compacting mechanism herein disclosed, first the intermittent tilting move-

ment of the compacting element which imparts to it what may be termed an "up-and-over" movement or clawing action, and secondly, the so-called "quick-return" movement which eliminates the otherwise prolonged interval between feeding strokes and thus considerably promotes the effectiveness of the compacting action and avoids the possibility of the dirt and litter accumulating within the lower end of the filter bag at a greater rate than the ability of the compacting mechanism to dispose of it.

Having, therefore, disclosed, a preferred embodiment of the invention, I claim:

1. In a suction cleaner, the combination of suction-creating means, a filter bag connected with the outlet from said suction-creating means, a dirt receptacle communicating with said filter bag at its lower end, a dirt compacting member for feeding the dirt from said bag into said receptacle during the operation of said cleaner, means to develop usable power during cleaner operation, mechanism for transmitting the power from said source to said compacting member, a frame supporting said compacting member and mounted for limited tilting movement, and means for tilting said frame at predetermined intervals to vary the path of movement of said compacting member.

2. In a suction cleaner, the combination of suction-creating means, a filter bag connected with the outlet from said suction-creating means, a dirt receptacle communicating with said filter bag at its lower end, a reciprocating dirt compacting member for feeding the dirt from said bag into said receptacle during the operation of said cleaner, means to develop usable power during cleaner operation, mechanism for transmitting power from said source to said compacting member, a frame supporting said compacting member and tiltable bodily to vary the path of said compacting member in its feeding and return strokes, and means for tilting said frame at predetermined intervals in the reciprocating movement of said compacting member.

3. In a suction cleaner, the combination of suction-creating means, a filter bag connected with the outlet from said suction-creating means, a dirt receptacle communicating with the lower end of said filter bag, a reciprocating dirt compacting member, means to develop usable power during cleaner operation, mechanism for transmitting power from said source to said compacting member, and means for imparting a variable reciprocating movement to said compacting member whereby the stroke in one direction is relatively quicker than the stroke in the opposite direction.

4. In a suction cleaner, the combination of suction-creating means, a filter bag connected with the outlet from said suction-creating means, a dirt receptacle communicating with the lower end of said filter bag, a reciprocating dirt compacting member mounted adjacent the opening from said bag, means to develop usable power during cleaner operation, mechanism for transmitting power from said source to said compacting member, a frame supporting said compacting member and mounted for limited rocking movement about an axis transverse to the path of said compacting member, means for rocking said frame at predetermined intervals in movement of said compacting member, and means acting to impart to said compacting element a relatively quicker stroke in one direction.

5. In a suction cleaner, the combination of suction-creating means, a filter bag connected with the outlet from said suction-creating means, a dirt receptacle communicating with the filter bag at its lower end, dirt compacting mechanism for feeding the dirt from said filter bag into said receptacle during the operation of the cleaner comprising a reciprocating compacting member moving toward and from the discharge opening to said receptacle, means to develop usable power during cleaner operation, an endless chain operatively connected with said compacting member and pawl and ratchet mechanism driven from said source of power through an intermediate crank and connecting rod, and a spring-actuated quick-return mechanism connected with said compacting member and operative to impart to said reciprocating compacting element a relatively quick stroke in one direction.

6. In a suction cleaner, the combination of suction-creating means, a filter bag connected with the outlet from said suction-creating means, a dirt receptacle communicating with the filter bag at its lower end, dirt compacting mechanism for feeding the dirt from said filter bag into said receptacle during the operation of the cleaner comprising a reciprocating compacting member, a frame supporting said compacting member and mounted for bodily tilting movement about an axis transverse to the path of said compacting member, means to develop usable power during cleaner operation, an endless chain carried by said frame and connected with said compacting member, pawl and ratchet mechanism driving said chain and driven from said source of power through an intermediate crank and connecting rod, and means for tilting said frame through a limited angle during each alternate stroke of said compacting member comprising a shoe carried by said chain and contacting a fixed track parallel with said chain.

7. In a suction cleaner, the combination of suction-creating means, a filter bag connected with the outlet from said suction-creating means, a dirt receptacle communicating with the lower end of said filter bag, a handle pivotally mounted on the cleaner body to swing in a vertical direction, a dirt compacting member operative to feed the dirt from said filter bag into said receptacle, and mechanism for transmitting the swinging movement of said handle to said dirt compacting member comprising a gear sector carried by said handle, a gear wheel meshing with said gear sector and driving a crank arm, pawl and ratchet mechanism connected with said crank arm by a connecting rod, an endless chain, an endwise sliding cross head attached to said chain and connected with one arm of said compacting member, said pawl and ratchet mechanism having operative connection with said chain to impart an intermittent movement thereto in one direction, a tiltable frame supporting said driven chain and compacting member, a cam member carried by said chain and adapted to contact a fixed track adjacent said chain for tilting said frame during alternate strokes of said compacting member, and tension means opposing the tilting of said frame.

8. In a suction cleaner, the combination of suction-creating means, a filter bag connected with the outlet from said suction-creating means, a dirt receptacle communicating with the lower end of said filter bag, a handle pivotally mounted on the cleaner body to swing in a vertical direc-

tion, a dirt compacting member operative to feed the dirt from said filter bag into said receptacle, mechanism for transforming the swinging movement of said handle into a reciprocating movement of said compacting member, the latter comprising a claw-like member mounted at the end of a sliding rod, a frame supporting said sliding rod and mounted for intermittent rocking movement, means for rocking said frame during alternate strokes of said compacting member, and means for importing variable feeding and return strokes to said compacting member.

9. In a suction cleaner, suction-creating means, dirt-filtering means connected to said suction-creating means and adapted to receive dirt-laden air therefrom, a receptacle opening into said filtering means adjacent a point therein at which collected foreign material accumulates, dirt-moving means mounted for movement at said point toward and from said receptacle in a path which

includes an action stroke at a lower level and a return stroke at a higher level and power-transmitting means to actuate said dirt-moving means.

10. In a suction cleaner, suction-creating means, dirt-filtering means connected to said suction-creating means and adapted to receive dirt-laden air therefrom, a receptacle opening into said filtering means adjacent a point therein at which collected foreign material accumulates, dirt-moving means in said filtering means, means mounting said dirt-moving means for movement toward said receptacle in a straight line and for movement from said receptacle in a path including a straight line inclined upwardly at an angle to said first-mentioned straight line and a downward movement which places said dirt-moving means at the start of said first-mentioned straight line, and power-transmitting means to actuate said dirt-moving means.

HARRY B. WHITE.
